UNITED STATES PATENT OFFICE.

JAMES GRESHAM, OF MANCHESTER, COUNTY OF LANCASTER, ASSIGNOR TO
THE VACUUM BRAKE COMPANY, (LIMITED,) OF LONDON, ENGLAND.

VALVE APPARATUS FOR VACUUM RAILWAY-BRAKES.

SPECIFICATION forming part of Letters Patent No. 415,968, dated November 26, 1889.

Application filed January 8, 1889. Serial No. 295,535. (No model.) Patented in England April 28, 1888, No. 6,320.

To all whom it may concern:

Be it known that I, JAMES GRESHAM, a subject of the Queen of Great Britain and Ireland, of the firm of Gresham & Craven, engineers and machinists, of Craven Iron Works, Salford, Manchester, in the county of Lancaster, England, have invented new and useful Valve Apparatus for Vacuum Railway-Brakes, (for which Letters Patent have been applied for in Great Britain, to bear date April 28, 1888, No. 6,320,) of which the following is a specification.

This invention relates to valve apparatus applicable for use with automatic brake-cylinders and vacuum-chambers, the same being specially adapted for use with trains composed of a great number of vehicles, the object being to enable the brakes to be applied in cases of emergency throughout the train with greater rapidity than is attainable when the air is admitted through the train-pipe alone to the brake-cylinders.

With vacuum automatic brake apparatus as ordinarily constructed for applying the brakes air is admitted through one opening, controlled by a valve or otherwise, to the train-pipe, and thus to the brake-cylinders of several vehicles. For ordinary stoppages and with trains of average length the brakes are thus applied with sufficient rapidity and the train is retarded or arrested without shock. For expediting the application of the brakes valves for admitting air to the train-pipe are usually placed in the guards' vans, these valves being contrived so as to act automatically when air is suddenly admitted to the train-pipe by way of the driver's valve or in consequence of the couplings becoming disconnected or broken.

One object of the present invention is to provide means whereby air may be admitted directly—that is, without passing through the brake-pipe—to the brake-cylinder of each vehicle, the brakes being thereby brought into action with greater rapidity and almost simultaneously throughout a train of any length.

In order that my improvements may be fully understood, I will proceed to describe the same with reference to the accompanying drawings, whereof—

Figure 1 is a vertical section of a brake-cylinder, showing the application of my invention thereto, Figs. 2 and 3 being vertical sections, drawn to an enlarged scale, of my improved valve mechanism.

Similar letters of reference are employed in all the figures to indicate corresponding parts so far as they appear.

a is the vacuum-chamber, provided with trunnions a' .

a^2 is the brake-cylinder, arranged within the chamber a .

a^3 is the piston, furnished with a rolling packing-ring a^4 and a piston-rod a^5 , to which the lever for actuating the brake rods and blocks is connected.

The parts above referred to by reference-letters are ordinary and well-known parts appertaining to vacuum-brake apparatus.

To the under side of the brake cylinder or chamber a is secured a casting b , in which are formed passages b' and b^3 , the former leading from the train-pipe to the under side of the piston a^3 (or diaphragm, when used) and the latter leading from a side branch from the passage b' past a ball-valve to the vacuum-chamber and to the upper side of the piston a^3 . The ball-valve is mounted in a tubular carrier b^3 , which at one end fits and slides upon a tubular projection formed upon the casting b , the extremity thereof serving as a seating for the ball-valve b^4 when in the position shown in Fig. 2. The other end of the valve-carrier b^3 is enlarged and has lateral orifices for the admission of air from the surrounding chamber, and to the enlarged end of the carrier b^3 is attached a stem b^5 , which secures the middle part of a diaphragm b^6 air-tight between the end of the tube b^3 and a collar formed upon the stem b^5 . The outer edge of the diaphragm b^6 is secured air-tight between the face of a body b^7 and the bottom of a recess formed in the casting b , wherein the part b^7 is screwed. The part b^7 forms a guide for the outer end of the stem b^5 , the latter being forked for the reception of a lever b^8 . (Shown in cross-section.) In Fig. 2 this lever is shown in dotted lines in elevation at right angles to its correct position. The movement of the lever b^8 in either direction withdraws the ball-valve b^4 from its seat

when it is required to admit air to the vacuum-chamber.

The above-described method of constructing and operating ball-valve mechanism resembles that described in the specification to Letters Patent of the United States numbered 332,653, and dated December 15, 1885, but is referred to in order that my present improvements may be more readily understood.

To the casting *b* another casting *c* is attached, and between the flanges or adjacent faces thereof the outer edge of a diaphragm *c'*, of india-rubber or other suitable flexible material, is secured air-tight. The middle portion of the diaphragm *c'* is fastened between a shoulder formed upon the hollow body *c²*, and the face of a ring or ferrule *c³*, which is screwed upon the neck of the same. The lower part of the hollow body *c²* is enlarged and terminates in a flange whereof the face is recessed for the reception of a washer *c⁴*, composed of india-rubber or other suitable elastic packing material. To the interior of the enlarged part of the hollow body *c²* is screwed a bush *c⁵*, the latter being formed with an outwardly-projecting flange, which assists in holding the washer *c⁴* in position.

The casting *c* is formed with a seating *c⁶*, against which the elastic packing *c⁴* rests when the hollow body *c²* occupies the position indicated in Fig. 2. Within the enlarged or lower portion of the hollow body *c²* is arranged a ball-valve *c⁷*, which rests, when in its normal position, on cross-bars *c⁸*, formed in the casting *c*. Carried by cross-bars on the casting *b* is a pendent projection *c⁹*, which extends into the neck of the hollow body *c²*. The side of the casting *c* is provided with numerous small holes *c¹⁰* for the admission of the external air to the exterior of the hollow body *c²* and to one side of the diaphragm *c'*. The casting *c* is further provided with a branch *c¹¹*, to which a flexible tube communicating with the train-pipe is connected. When a partial vacuum is formed in the train-pipe, the atmospheric pressure upon the exterior of the hollow body *c²* being greater than that upon the under side of the diaphragm *c'*, the body *c²* is maintained with its lower face resting upon the seat *c⁶*, this position being also maintained when air is admitted to the train-pipe for ordinary applications of the brakes. The weight of the hollow body *c²* also insures its remaining upon its seating *c⁶* when the atmospheric pressures respectively inside it and outside it are equal. If, however, air be suddenly admitted to the train-pipe and in full quantity, as in a case of emergency or the severance of the train-pipe, the ball-valve *c⁷* is instantly lifted and seats against the neck or upper portion of the body *c²*, whereupon the pressure of air from the train-pipe, acting upon the ball-valve *c⁷* and the exposed portion of the body *c²*, combined with the pressure of the external air entering through the holes *c¹⁰* and acting

upon the lower side of the diaphragm *c'*, operates to lift the body *c²* from its seat *c⁶* and to permit the external air to pass directly both to the train-pipe and by way of the passage *b'* to the brake-cylinder, where it acts upon the lower side of the piston to apply the brakes. It will be understood that after the valve *c⁷* and body *c²* have been lifted, as above described, the valve *c⁷* is unseated by means of the pendent projection *c⁹*.

In a train provided with automatic admission-valves of the kind above described upon the admission-valve nearest to the point at which air is admitted to the train-pipe opening an additional quantity of air is enabled to gain access to the train-pipe, and thus in turn to induce and expedite similar action on the part of all the other admission-valves. When the brakes have been applied, the valve *c⁷* and the body *c²* resume their original positions, communication by way of the holes *c¹⁰* being thus cut off ready for a vacuum to be again created in the train-pipe.

Fig. 3 illustrates a modified or alternative method of construction. The parts of the casting *b* are substantially the same as those shown in Fig. 2, except that the projection *c⁹* is dispensed with. There is a hollow body *c²*, furnished with an elastic facing *c⁴*, arranged and held as described with reference to Fig. 2, and provided internally with a ball-valve *c⁷* and a seating above same. Instead, however, of the hollow body *c²* being connected with a diaphragm *c'*, it is provided with an elastic-packed face *d*, held between a shoulder on the neck of the body *c²* and a washer *d¹*, the latter being secured by a nut *d²*. The elastic-packed face *d* works against a seating formed on a disk or ring *d³*, mounted in a recess in the casting *c*, as shown, the joint being rendered air-tight by means of an elastic packing placed between the adjacent faces of the castings *b* *c*. When both the faces *c⁴* and *d* rest upon their respective seatings, the body *c²* forms a differential valve, and the pressure of the atmosphere, entering through the holes *c¹⁰*, tends to keep same closed, the gravity of the body *c²* having a similar effect when the pressures on the respective sides thereof are equal. In some instances an annular channel *d⁴* is made in the under face of the metal of the lower valve above the elastic facing *c⁴* and small holes are drilled to allow the atmosphere to pass from the holes *c¹⁰* to this annular channel *d⁴*. Under such circumstances the india-rubber facing *c⁴* is pressed very slightly upward into the annular channel when the valves are down on their seatings, and the pressure of the external air, acting in the annular channel *d⁴* to press the elastic facing *c⁴* upon its seating, insures the closing of both valves firmly upon their respective seatings when there is a partial vacuum in the train-pipe. The back of the lower valve is furnished with notched wings *d⁶*, which serve to guide the body *c²* in the disk *d³* and to limit the extent of its vertical motion.

When a large admission of air is made to the train-pipe, the valve c^7 is lifted against its seating and the body c^2 is raised until the extended portions of the wings d^6 arrive against the under side of the disk d^3 , whereupon air is admitted directly from the external atmosphere past the lower valve to the train-pipe and between the wings d^6 and past the upper valve to the brake-cylinder, where it acts upon the under side of the piston. When the brakes have been applied, the gravity of the body c^2 causes it to resume its original position, as previously described with reference to Fig. 2.

What I claim as my invention, and desire to secure by Letters Patent of the United States, is—

1. In vacuum automatic brake apparatus, the combination, with the brake-cylinder, of a differential valve c^2 , placed between the atmosphere and the brake-cylinder and train-pipe, and which remains inoperative during the ordinary working of the brakes, and a valve c^7 , placed between the brake-cylinder and the train-pipe and which remains open under the same conditions, the two valves jointly serving, when the brakes are to be suddenly applied, to permit direct communication between the atmosphere and the brake-cylinder and train-pipe.

2. In valve apparatus for admitting air directly to the brake-cylinder of an automatic vacuum-brake, the combination of a differential valve c^2 with a ball or other valve c^7 , the valve c^2 having a passage through which air is exhausted from or admitted to the brake-cylinder during the ordinary working of the brakes, the valve c^7 serving to temporarily close such passage and enable the valve c^2 to be opened when air is suddenly admitted to the train-pipe.

3. In valve apparatus for automatic vacuum-brakes, the combination of the main valve b^4 with the supplementary valves c^2 and c^7 , the valve b^4 enabling air to be simultaneously exhausted from the vacuum-chamber and brake-cylinder or separately admitted to one side of the brake-piston, the valves c^2 and c^7 serving to open direct communication between the atmosphere and the brake-cylinder and train-pipe when circumstances require an exceptionally rapid application of the brakes throughout the train.

JAMES GRESHAM.
